TANK BALL

John J. O'Hare, Ridgefield, Conn., assignor to
 American Rubber Products Corporation, New
 York, N. Y., a corporation of New York

Application March 28, 1942, Serial No. 436,675

5 Claims. (Cl. 4—56)

This invention relates to tank balls in general and more especially to tank balls having a lower yieldable valve portion and an upper rigid part or upper part that is rigid as compared to the lower yieldable valve portion.

Among the objects of the present invention, it is aimed to provide an improved tank ball having a lower yieldable or rubber valve portion, and an upper conical double shell portion for engaging a flange portion of the lower rubber portion to reinforce the same and to aid in positioning or maintaining the rubber valve portion in proper inflated position to form an effective valve seat and at the same time also form a bearing for the conventional connecting rod.

It is still another object of the present invention to provide an improved tank ball having a lower resilient or rubber valve portion and an upper conical double shell portion composed of a plastic material such as "Tennite," "Plastacele," "Lucite," "Bakelite," or the like, in which the spud is formed as an integral part of the inner shell.

These and other features, capabilities and advantages of the present invention will appear from the subjoined detail description of one specific embodiment thereof illustrated in the accompanying drawing in which

Figure 1 is a transverse section of an assembled tank ball made according to the present invention; and

Fig. 2 is an exploded view of the several elements of the tank ball before being assembled with the lower yieldable or rubber valve portion partly in section.

In the embodiment shown, the lower yieldable valve portion 1 is preferably composed of rubber and is substantially semi-spherical in shape below the equator line 2, having a small air inlet 3 at the pole, as indicated, and a conical flange portion 4 flaring upwardly and inwardly from the equator line 2.

The flange 4, preferably, has a greater wall thickness, as shown, than the wall thickness of the semi-spherical portion 5. The outer face of the flange 4 is preferably a smooth conical surface except when raised lettering is molded on the lower zone thereof adjacent the equator line 2, such as the lettering 6. The inner face of the flange 4, preferably terminates in a bead 7 at the free edge thereof, which bead 7, in the present instance, extends beyond the free annular edge 8 to form the shoulder 9.

The upper portion of the tank ball, in the present instance, consists mainly of the inner shell

10 and the outer shell 11. The inner shell 10 has formed integral therewith the spud or cylindrical extension 12, which has heretofore always been made independently and separately from the shell 10. The shell 10, in the present instance, has a conical wall portion 13 having an inwardly extending annular bead 14 spaced from the free outer edge 15 of the shell 10 as shown. The wall portion 13 terminates in the flat imperforate wall portion 16 from which the cylindrical extension 12 extends outwardly. The bead 14 is molded during the formation of the shell 10, forming an annular groove or depression on the outer face thereof for receiving the enlargement or bead 7 of the rubber flange 4.

For tank ball sizes ranging from 2 1/4" to 3", the wall portion 13 and flat top 16 need not exceed .035 to .040 of an inch in thickness when the shell 13 is composed of a plastic, such as "Tennite," "Plastacele," "Lucite" or "Bakelite," in which case, however, the thickness of the wall of the extension 12 should preferably be twice as thick, as shown.

The extension 12, in the present instance, is provided with an outer lefthand thread and an inner righthand thread, the outer lefthand thread being provided to screw threadedly receive the collar 17, and the inner righthand thread being provided to receive the conventional connecting rod 18. The collar 17 is also preferably composed of a plastic material, but if it is to be threaded and cut by an automatic screw machine, it has been found desirable to make it of "Marblette" instead of "Tennite" or the like since it has been found that "Marblette" will better withstand the heat generated when cutting these collars by an automatic screw machine. The conventional connecting rod 18, on the other hand, is preferably composed of metal in accordance with the conventional practice. The conical wall portion 13 of the inner shell 10 and extension 12 preferably have a fillet 112 graduating from the extension 12 into the upper face of the flat imperforate wall portion 16 to strengthen the angle between the extension 12 and the wall portion 16. These wall portions 13 and 16 and extension 12 integral with one another of the inner shell 10 are molded in one piece, according to the present invention, from a plastic material such as "Tennite," "Plastacele," "Lucite," "Bakelite," and the like.

The outer shell 11, similarly, is preferably composed of a plastic material, such as "Tennite," "Plastacele," "Lucite," "Bakelite," or the like, and in shape has a conical wall 19 and a flat top 20

provided with a central opening 21 to enable the cylindrical extension 12 to pass therethrough as shown in Fig. 1. The thickness of the walls 19 and 20 is also preferably not more than .035 to .040 of an inch in thickness if intended for a tank ball ranging in size between 2½" and 3".

Serving as a water-tight and air-tight stuffing and placed, in the present instance, around the cylindrical extension 12 above the flat top 20 of the upper shell 11, there is provided a washer 22 composed of leather, rubber or the like. When assembled, as shown in Fig. 1, the outer free edges of the shells 10 and 11 will clamp or grip the flange 4, the outer free edge of the outer shell 11 terminating clear of the raised lettering elements 6 and the bead 14 of the inner shell engaging the bead 7 of the flange 4. Furthermore, the washer 22 will rest on the flat top 20 of the outer shell 11 around the extension 12 and be pressed against such flat top 20 in intimate engagement with the extension 12 by the collar or nut 17. The connecting rod 18, as shown in Fig. 1, will of course be screw threadedly connected to the inner righthand thread of the extension 12. The provision of the lefthand thread for the collar 17 and of the righthand thread for the connecting rod 18 is, of course, in order to prevent loosening the collar 17 when screwing the connecting rod 18 into place. It is obvious, however, that this particular inner and outer thread relationship of the extension 12 is not essential to the present invention and is merely disclosed as part of an embodiment of the invention. From the foregoing, it will be seen that the shell elements 10 and 11, due to the imperforate character of the inner shell 10, throughout its conical wall 13 and flat top 16 and the yieldable connection between the outer edges of the shells 10 and 11 afforded by the yieldable or rubber constituency of the flange 4 and the yieldable connection between the top 20 of the shell 11 and nut or collar 17 afforded by the yieldable washer 22, will form a water tight and air tight dome to supplement the water tight and air tight character of the yieldable ball portion 1, thereby to insure a pneumatic valve element for the valve seat, not shown, of the tank with which this tank ball is used.

The shell 11 and the shell 10, including the extension 12 may also be composed of hard rubber or the like without departing from the spirit of the invention.

Furthermore, the angle portion between the conical wall 13 and the flat wall 16 of the shell 10 and the angle portion between the conical wall 19 and the flat wall 20 of the shell 11 are slightly thickened, as shown, similar to the fillet 112, to serve as reinforcements for the portions of the shells 10 and 11 where they are subjected to the greatest strains and stresses and where they would otherwise be weakest.

The product "Marblette" is a cast phenolic plastic manufactured by The Marblette Corporation of Long Island City, N. Y.; the plastic products "Plastacele" and "Lucite" are manufactured by E. I. du Pont de Nemours & Company of Wilmington, Delaware; the plastic product "Tennite" is manufactured by the Tennessee Eastman Corporation of Kingsport, Tennessee; and the plastic product "Bakelite" is manufactured by the Bakelite Corporation of New York, New York.

It is obvious that various changes and modifications may be made to the details of construction without departing from the general

spirit of the invention as set forth in the appended claims.

I claim:

1. The combination of a yieldable hollow valve member having a conical flange extending radially inward from one end thereof, two conical plastic, imperforate shell members nested into one another with the outer zones thereof gripping said flange in place, the inner shell having a flat top with a chambered cylindrical extension extending outwardly therefrom and integral therewith, the extension being externally and internally threaded, the outer shell having a flat top with an opening therein to receive said cylindrical extension, a yieldable washer mounted on said cylindrical extension and disposed on the top of said outer shell, and a collar screw threadedly engaging the said cylindrical extension and washer and operative to draw said shells toward one another and to grip said flange between them, the internal thread of said extension being provided screw threadedly to receive a connecting rod.
2. The combination of a rubber hollow valve member having a conical flange extending radially inward from one end thereof, two conical plastic imperforate shell members nested into one another with the outer zones gripping said flange in place, the inner shell having a flat top with a chambered cylindrical extension extending outwardly therefrom and integral therewith, the extension being externally and internally threaded, the outer shell having a flat top with an opening therein to receive said cylindrical extension, and a collar screw threadedly engaging the said cylindrical extension and operative to draw said shells toward one another and to grip said flange between them, the thickness of said shell members not exceeding .040 inch and the wall thickness of said extension not exceeding twice the thickness of said shell members.
3. The combination of a rubber hollow valve member having a conical flange extending radially inward from one end thereof, two conical plastic shell members nested into one another with the outer zones thereof gripping said flange in place, the inner shell having a flat top with a chambered cylindrical extension extending outwardly therefrom and integral therewith, the extension being externally and internally threaded, the outer shell having a flat top with an opening therein to receive said cylindrical extension, a leather washer mounted on said cylindrical extension and disposed on the top of said outer shell, and a plastic collar screw threadedly engaging said cylindrical extension and washer and operative to draw said shells toward one another and to grip said flange between them, the internal thread of said extension being provided screw threadedly to receive a connecting rod and the thickness of said shell members not exceeding .040 inch and the wall thickness of said extension not exceeding twice the thickness of said shell members.
4. The combination of a yieldable hollow semi-spherical rubber valve member having a conical flange extending radially thereof, two conical plastic shell members nested into one another with the outer zones thereof gripping said flange in place, the inner shell having a flat top with a chambered cylindrical extension extending outwardly therefrom, said cylindrical extension having an inner righthand thread and an outer lefthand thread, a washer mounted on said cylindrical extension and disposed on the top of

said outer shell, a collar screw threadedly engaging the lefthand thread of said cylindrical extension and said washer and operative to draw said shells toward one another and to grip said flange between them, and a connecting rod screw threadedly engaging the righthand thread of said cylindrical extension, the internal thread of said extension being provided screw threadedly to receive a connecting rod and the thickness of said shell members not exceeding .040 inch and the wall thickness of said extension not exceeding twice the thickness of said shell members.

5. The combination of a hollow semi-spherical rubber valve member having an opening at the pole thereof and a conical flange extending radially inward from the equator thereof, a bead on the inner face along the inner edge of said flange extending beyond the edge of said flange, two conical plastic shell members nested into 20

one another with the outer zones thereof gripping said flange in place, the inner shell having an annular groove to receive the bead on the inner face of said flange and a flat top with a chambered cylindrical extension extending outwardly therefrom and integral therewith, the extension being externally and internally threaded, the outer shell having a flat top with an opening therein to receive said cylindrical extension, and a collar screw threadedly engaging said cylindrical extension and operative to draw said shells toward one another and to grip said flange between them, the internal thread of said extension being provided screw threadedly to receive a connecting rod and the thickness of said shell members not exceeding .040 inch and the wall thickness of said extension not exceeding twice the thickness of said shell members.

JOHN J. O'HARE.
